(57) **CLAIM**

The ornamental design for a tip receptor mount for lightning protection systems, as shown and described.

DESCRIPTION

FIG. 1 is a bottom, front, left isometric view of an ornamental design for a tip receptor mount for lightning protection systems;

FIG. 2 is a bottom, rear, left isometric view of the tip receptor mount of FIG. 1;

FIG. 3 is a bottom, front, right isometric view of the tip receptor mount of FIG. 1;

FIG. 4 is a bottom, rear, right isometric view of the tip receptor mount of FIG. 1;

FIG. 5 is a bottom plan view of the tip receptor mount of FIG. 1;

FIG. 6 is a top plan view of the tip receptor mount of FIG. 1;

FIG. 7 is a left side elevational view of the tip receptor mount of FIG. 1;

FIG. 8 is a right side elevational view of the tip receptor mount of FIG. 1;

FIG. 9 is a front elevational view of the tip receptor mount of FIG. 1; and,

FIG. 10 is a rear elevational view of the tip receptor mount of FIG. 1.

The ornamental design that is claimed is shown in solid lines in the drawings. The broken lines in the drawings are for illustrative purposes only and form no part of the claimed design. Any dash-dot broken lines in the drawings are included to illustrate unclaimed surfaces or environment of the claimed design. Any dash-dot-dot broken lines in the drawings are included to define unclaimed boundaries of the claimed design.
